UNITED STATES PATENT OFFICE.

HARRY J. VAN PELT, OF NEWARK, NEW JERSEY.

SOUNDING TOY.

Specification of Letters Patent.

Patented Jan. 14, 1919.

1,291,289.

Application filed August 20, 1917. Serial No. 187,312.

To all whom it may concern:

Be it known that I, HARRY J. VAN PELT, a citizen of the United States, residing at Newark, in the county of Essex, State of New Jersey, have invented certain new and useful Improvements in Sounding Toys; and I do hereby declare the following to be a full, clear, and exact description of the invention, such as will enable others skilled in the art to which it appertains to make and use the same.

This invention is an improvement in toys and has particular reference to a sounding toy.

15 An object of the invention is to provide a toy of simple and inexpensive construction which is adapted to be whirled around in the air at various speeds in order to produce sounds of different tone and pitch.

20 The inventive idea involved is capable of receiving a variety of mechanical expressions, one of which, for the purpose of illustrating the invention, is shown in the accompanying drawing, wherein:—

25 Figure 1 is a side elevation of a toy constructed in accordance with the invention.

Fig. 2 is a similar view looking at the other side of the toy.

Fig. 3 is a detail perspective view of the 30 body portion of the toy showing the same in partially opened position.

Fig. 4 is a section on the line 4—4 of Fig. 1.

Fig. 5 is an end elevation.

35 The invention is illustrated in the accompanying drawing in what is now believed to be its preferred form which comprises the body portion 5 formed of an elongated strip of material bent upon itself to a substantially Y-shaped formation to provide the 40 parallel clamping arms 6 and the diverging arms 7. A guiding vane 8 formed of card board or any other suitable material adapted to contain advertising matter has one end thereof preferably bent upon itself as indicated at 9, and disposed between the clamping arm 6 so that said vane will be retained in proper position and extend rearwardly from the body portion 5. In order to retain 45 the vane in its clamped position, one end of the strip of metal forming the body portion 5 is provided adjacent one of its longitudinal edges with a lug 10 while the other end of said strip is provided intermediate its

longitudinal edges with the lug 11, said 55 lugs being adapted to be bent over the opposite ends of the strip in order to retain the arms in clamping position. The ends of the strip are further provided with apertures 12 which are adapted to register to receive 60 an end of a cord or other flexible element 13. A rubber band 14 or other flexible sound producing element is stretched around the body portion 5, engaging one of the ends of the different arms 6 and 7 so that when 65 the body portion is whirled, in a manner to presently appear, sounds of varying tone and pitch will be produced by the rubber owing to the vibrations thereof, said sound and pitch depending upon the velocity with 70 which the body portion is whirled. The vane 8 carried by the body portion is adapted to guide the same and prevent turning thereof about its own longitudinal axis or at an angle to the plane of travel thereof, 75 said vane being at all times coincident with its arc of movement and the rubber band 14 will therefore have its forward edge presented to the atmosphere as the toy is operated.

80 The cord 13 is made of any length desired and is attached at its other end to a revolving hook 15 mounted upon one end and extending laterally from the handles 16 which is adapted to be grasped by the body portion 85 in order to operate the toy.

What is claimed is:—

1. A toy of the class described comprising a body portion formed from an elongated strip bent upon itself at points intermediate its ends to provide diverging arms, the ends of said strips extending from the inner ends of said diverging arms to form clamping arms, a lug extending from one of said clamping arms intermediate its 90 longitudinal edges and adapted to be bent over the end of the other clamping arm, a second lug extending from said other clamping arm adjacent one of its longitudinal edges and adapted to be bent over the end of 95 the first named clamping arm whereby to secure said clamping arms in their operative positions, a vane secured between said clamping arms for guiding the body portion while the same is being whirled, and means 100 connected to said body portion for whirling the same.

2. A toy of the class described comprising

ing a body portion formed from an elongated strip bent upon itself at points intermediate its ends to provide diverging arms, the ends of said strips extending from the 5 inner ends of said diverging arms to form clamping arms, means connected to the clamping arms for whirling the body portion, and means interposed between said

clamping arms for guiding said body portion while the same is being whirled.

10

In testimony whereof, I affix my signature in the presence of two witnesses.

HARRY J. VAN PEELT.
